UNITED STATES PATENT OFFICE.

JOHN M. FRANK, OF CHICAGO, ILLINOIS, ASSIGNOR TO ILG ELECTRIC VENTILATING COMPANY, OF CHICAGO, ILLINOIS, A CORPORATION OF LOUISIANA.

UNIT FOR HEATING AND VENTILATING SYSTEMS.

1,295,151.

Specification of Letters Patent.

Patented Feb. 25, 1919.

Application filed January 9, 1918. Serial No. 211,064.

To all whom it may concern:

Be it known that I, JOHN M. FRANK, a citizen of the United States, residing at Chicago, in the county of Cook and State 5 of Illinois, have invented certain new and useful Improvements in Units for Heating and Ventilating Systems, of which the following is a specification.

This invention has reference to heating 10 and ventilating systems for factories, workshops, offices and similar large buildings of that general type wherein warm air is forced directly into the room to be heated and ventilated, this type of heating being 15 commonly known as "blast heating." In ordinary blast heating installations, where the air is brought in through pipes, good practice places a limit of about 1,200 lineal feet per minute as the speed through the 20 pipes, on account of friction; and consequently a great deal of piping is needed to secure proper distribution for the reason that the air can not be thrown a very great 25 distance before it rises to the ceiling. A large amount of piping means a great deal of power lost constantly in friction, as well as a large expense for installation.

My present invention is designed as an 30 improvement in heating and ventilating systems of this general character or type and among the objects sought by the invention may be mentioned, a considerable reduction in the power consumption, a better and more efficient distribution of the warm air 35 delivered into the room resulting from a higher speed of flow, ease and cheapness of installation resulting mainly from the portable character of the units, and capability of use either in a heating system alone or 40 in a ventilating system alone or in a combined heating and ventilating system.

Other objects and advantages as secured 45 by the invention will be readily apparent to those skilled in the art from the subjoined description when taken in connection with the accompanying drawings wherein I have illustrated one practical and workable embodiment of the invention, and wherein—

Figure 1 is a plan view of one practical 50 installation of a system employing my improved heating units as applied to a workshop and an adjoining office.

Fig. 2 is a side elevation, partly broken

away, of one of the units shown as suspended 55 from the ceiling of the room.

Fig. 3 is a horizontal section on the line 3—3 of Fig. 2.

Fig. 4 is a front elevation, with the deflector plate broken off.

Fig. 5 is a horizontal section of a unit 60 shown as applied to a side wall of the room and designed for both heating and ventilation or for recirculating and warming inside air alone; and

Fig. 6 is a side elevation of the structure 65 shown in Fig. 5.

Referring to the drawings and first describing the heating unit itself, this comprises a rectangular sheet metal casing having a top wall 10, a bottom wall 11 and side walls 12, the casing being open at both its front and rear ends. In the rear end of the casing is mounted a heat radiating element which may consist of one or more 70 steam coils or radiator stacks diagrammatically indicated at 13. In the front portion of the casing is mounted a propeller-fan 14 that occupies a circular opening in a transverse partition 15, said opening having a 75 considerably smaller area than the area of the rear open end of the casing, and said fan being directly driven by an electric motor conventionally shown at 16 that is provided with a protective hood or housing 17 80 from which leads a suction pipe 18 opening through the bottom wall 11 of the casing, the motor and fan being supported from the partition 15 by a series of radial arms 19. This combined electric motor and direct-driven propeller-fan is substantially like that disclosed in Letters Patent No. 831,284 to Robert A. Ilg, dated September 18, 1906, an improved form of which is shown in the later patent to the same patentee No. 95 1,244,334, dated October 23, 1917, and need not herein be more particularly described.

In front of the fan are a series of stationary vertical shutter strips 20 for diffusing the blast sidewise, and hinged at 21 to the upper 100 forward end of the casing is a depending deflector plate 22 overhanging the forward open end of the casing and designed to control the up and down distribution of the blast, for which purpose the free end of 105 the deflector plate 22 is connected by a cord 23 running over a pulley 24 with a winding drum 25 mounted on the side wall of the

2
casing and adapted to be manipulated manually by handle 26, the deflector plate being counterweighted by a weight 27 interposed in the cord 23 between the pulley 24 and the drum 25. In the position shown in Fig. 2 the deflector plate is set to direct the blast downwardly or toward the floor. When the lower portion of the room becomes adequately heated, the deflector plate may be raised more or less by turning the handle 26 in the direction indicated by the arrow in Fig. 2 so as to direct the air blast across the room toward the side walls thereof. In one of the side walls 12 of the casing, between the heater and the fan there is an opening normally closed by a door 28. Whenever artificial heating of the air is not required, the heating elements 13 may be by-passed by opening the door 28 and permitting the fan to draw the air through the opening governed thereby for purposes of circulating the air in the room.

In Fig. 1 I have conventionally illustrated one practical and typical installation of a system employing the units hereinabove described. In this figure 29 designates the opposite side walls of a large room such as a factory, machine shop or the like, the interior space of which is designated by 30, and at one end thereof is a smaller room designated by 31 which may be assumed to represent office space separated from the main space by a partition 32. Extending longitudinally and substantially centrally 35 of the rooms 30 and 31 is a steam pipe line 33, while 34 may designate a return vacuum line which may or may not be employed as desired. Suspended from the ceiling by vertical extensions 35 of the casings of the heaters are the heating units hereinabove described, these units being spaced at intervals along the steam pipe line and alternately arranged on opposite sides of the latter, the units on one side being designated as an entirety by A and those on the opposite side by B. In the office space 31 I have indicated a single unit designated by C, the forward or delivery end of which is equipped with a three-way deflector D designed to 40 distribute the blast both forwardly and laterally. The several heating coils or radiators 13 of the units are, of course, connected with the steam pipe line 33 and the vacuum return line 34 where the latter is employed, and it will be observed that the units on one 45 side of the line face oppositely to those on the other side of the line, the units A forcing the heated air toward one of the side walls 29 of the building and the units B forcing the heated air toward the opposite side wall 29. As many units may, of course, be employed, as the conditions of any particular installation may require.

Instead of suspending the units from the ceiling, they may be supported otherwise, as

from the side walls or the floor. In Figs. 5 and 6 I have diagrammatically illustrated a side wall installation opposite a window or other opening 36. In this case the rear portion of the casing is equipped with a pair of dampers such as the slides 37 and 38, the former serving to open and close the outside opening 36, and the latter controlling a side opening between the casing and the room in which it is installed. Where warmed outside air is desired the damper 37 is opened and the damper 38 closed, thus affording ventilation. Where a mere stirring up or recirculation of the inside air is desired, the damper 37 is closed and the damper 38 opened. This mode of installation is more desirable in relatively small rooms where ventilation as well as heating may be required.

It is believed that the construction, principle of operation, and advantages of the invention will be apparent from the foregoing without further detailed description. In the heating of a factory, the question of heat is usually more important than ventilation, and the chief object is to raise the temperature at or near the floor to approximately 60° F. The heating system herein disclosed is well adapted for such situations, being cheaply built and easily installed without requiring duct work, necessitating only a minimum amount of piping. In the heating units herein shown the air may be caused to travel over the heating coils at a velocity of approximately 1,000 lineal feet per minute and leaves the fan at a high velocity of approximately 2200 to 2400 feet per minute, thereby securing a much greater speed of delivery or discharge and throwing the heated air much farther before it rises than is possible with ordinary blast heating construction. To secure effective results it is quite essential that the fan be placed in front of the heating coils so as to draw the air over or through the latter, since, if the fan were placed back of the coils and the air blown through the latter the velocity of discharge would necessarily be much lower and to that extent the efficiency of the system would be impaired. In the described arrangement wherein the heated air necessarily flows over the motor, the cooling feature is of considerable importance and contributes largely to the efficiency of the apparatus by reason of automatically keeping down the temperature of the motor which might otherwise become overheated.

I do not limit the invention to the precise details of structure and arrangement herein disclosed, since it is manifest that the same may be varied in minor details without departing from the principle of the invention or sacrificing any of the advantages secured thereby.

I claim:

1. A heating unit of the character described, comprising, in combination, a casing, a heat-radiating element in the rear portion of said casing, a combined motor and direct-driven propeller fan in the front portion of said casing acting to draw air over said heat-radiating element, said casing being open in rear of said element and in front of said motor and fan, a protective hood on said motor, and a pipe leading from said hood to the outside of said casing and supplying a current of cooling air to said motor.
2. A heating unit of the character de-

scribed, comprising, in combination, a sheet-metal casing having top, bottom and side walls and open front and rear, a heat-radiating element in the rear portion of said casing, a propeller-fan in the front portion of said casing acting to draw air through the open rear end over said element and force the heated air from the open front end, means for supporting said casing horizontally above the floor of a building to be heated, and an adjustable deflector-plate hinged to the forward end of said casing.

JOHN M. FRANK.
